BROADBAND MAGNETRON

Arnold Theodore Nordsieck, Champaign, Ill., assignor to International Standard Electric Corporation, New York, N. Y., a corporation of Delaware

Application June 10, 1949, Serial No. 98,194

1 Claim. (Cl. 315—39.3)

This invention relates to broadband amplifiers for micro-waves, and more particularly to a novel broadband amplifier of the magnetron type.

It is an object of the invention to provide a multi-cavity magnetron type structure which is non-oscillating and which is capable of amplifying over a wide frequency range.

The multi-cavity magnetron principle for generating micro-wave power is readily convertible to broadband amplification in a way very similar to that in which the velocity modulation principle has been applied in the travelling wave amplifier. The most significant feature of the travelling wave amplifier is that the coupling between the electron stream and the R. F. fields is maintained continuously with a definite phase relation over a large number of complete R. F. cycles. From one point of view however the multi-cavity magnetron may be regarded as an amplifier which is likewise several R. F. cycles long around the anode circumference (n cycles long if n is the mode number). Under these conditions the magnetron functions as a self-excited oscillator because it is made re-entrant upon itself. Any noise signal present in any part of the tube is amplified indefinitely by circulating around the tube, and the tube oscillates spontaneously. A small fraction of the power circulating in the device is bled off at one point in the circle, and this constitutes the output power. The phase relation between the electron stream and the R. F. field is maintained constant by adjusting the applied D. C. voltage and magnetic field so that the mean rate of circulation of the electrons around the tube is equal to the angular phase velocity of the R. F. field (the so-called Hartree condition). For a complete discussion of these ideas, reference may be made to the April 1946 issue of the Bell System Technical Journal, and to the article therein by Fisk, Hagestrum and Hartman, entitled "The Magnetron as a Generator of Centimeter Waves."

In the mode of highest n value, the so called π -mode, the excitation in an oscillating magnetron is not a circulating wave propagating around the anode structure but rather a standing wave pattern. In this special case, widely used in oscillators, the π -mode frequency is exactly the cut-off frequency of the transmission line forming the anode structure. In modifying the magnetron to make it suitable for use as an amplifier, it is not desirable to operate near a cut-off frequency of the transmission line forming the anode, since this condition would involve great frequency sensitivity. It may be noted however that even in a π -mode oscillation, where the excitation is necessarily a standing wave pattern, the electron stream is coupled appreciably only to that component of the pattern which represents a travelling wave circulating with the electron stream. The other component of the pattern, which represents an equal wave travelling against the electron stream, has a negligible effect on the electronic motions, influencing their orbits somewhat but exchanging no net energy with them. This is because the relative phase of the electron stream and this latter field com-

ponent changes very rapidly. These results are known from theoretical investigations by Hartree and others. In magnetron oscillators operating in a non π -mode, it has been established theoretically and confirmed experimentally by probe measurements in the resonator cavities that the excitation on the anode structure is a true rotating wave. In converting the multi-cavity magnetron oscillator for use as an amplifier, it is accordingly convenient to operate in a condition similar to the non π -mode.

- 10 In accordance with a feature of my invention I provide a magnetron type amplifier structure having R. F. circuits electrically smooth and reflectionless over a wide band, in which the re-entrant character associated with the magnetron oscillator is not present and in which that part of 15 the circuit which presents the radio frequency fields to electron stream provides a phase velocity which is small compared to the free space velocity of electromagnetic waves, and is independent of frequency over a wide band. The above-mentioned and other object and features of 20 the invention and the manner of attaining them will become more apparent and the invention itself will be best understood by reference to the following description of an embodiment of the invention taken in conjunction with the accompanying drawings, wherein:
- 25 Fig. 1 is a schematic diagram illustrative of certain features of the invention;
- Fig. 2 is a sectional side view of an embodiment of the invention; and Fig. 3 is a sectional end view of the embodiment shown in Fig. 2.
- 30 Referring first to Fig. 1, I show in schematic form a section of a linear magnetron having an anode 1 and a cathode 2 separated by a distance d centimeters. A D.-C. voltage difference of V volts is applied between anode and cathode, and a magnetic field of B gauss is directed 35 perpendicular to the plane of the section. A linear magnetron is shown for purposes of illustration because, since the magnetron is used as an amplifier, it cannot be re-entrant—and a linear magnetron is the simplest alternative to a re-entrant circulating magnetron. Moreover, the formulae which express the behavior of the magnetron are simplest for the linear case.

We consider the behavior of the magnetron of Fig. 1 when amplifying a wave having a free space wave length λ_o . The symbol λ_a (shown in Fig. 1) is used to denote transmission line wave length, or the distance along the anode corresponding to one complete cycle of the R. F. fields. The number

$$\frac{\lambda_a}{\lambda_o}$$

50 is then determined by the anode geometry, and is much less than unity. The formulas which are used in the following description are taken from the paper previously referred to by Fisk, Hagestrum and Hartman, in the April 1946 issue of the Bell System Technical Journal.

55 The unit magnetic field B_o is given by

$$B_o = \frac{1705}{d} \left(\frac{\lambda_a}{\lambda_o} \right)^2 \text{ gauss}$$

The unit voltage V_o is given by

$$V_o = 2.56 \times 10^5 \left(\frac{\lambda_a}{\lambda_o} \right)^2 \text{ volts}$$

The unit current I_o is given by

$$60 I_o = 170 \left(\frac{\lambda_a}{\lambda_o} \right)^3 \left(\frac{\lambda_a}{d} \right) \left(\frac{W}{d} \right) \text{ amperes per space charge spoke}$$

65 where W is the width of the anode.

The maximum electronic efficiency is given by

$$70 h = 1 - \frac{V/V_o}{(B/B_o)^2} = \left(\frac{1 - V/V_o}{1 + V/V_o} \right)^2 = (1 - B/B_o)^2$$

In order to obtain an overall efficiency of approximately

3

50%, an electronic efficiency of 60% is sufficient, since losses in the structure are small. This corresponds to a value for V/V_0 of about 8. Assuming that $V_0=160$ volts, the required voltage V is 1280 volts, and

$$\frac{\lambda_a}{\lambda_o} = \sqrt{\frac{160}{2.56}} \times 10^5 = .026$$

For a midband free space wavelength $\lambda_o=6$ cm., the guide wavelength λ_a becomes $6 \times .025 = 0.15$ cm.

The anode-cathode spacing d may be found from the empirical rule that

$$\frac{d}{\lambda_a} = 0.67 \text{ approximately}$$

which has been found to give good results in other magnetrons. Thus

$$d = 0.67(0.15) = 0.10 \text{ cm.} = .04 \text{ inch}$$

The unit magnetic field B_0 is

$$B_0 = \left(\frac{1705}{d} \right) \left(\frac{\lambda_a}{\lambda_o} \right) = 425 \text{ gauss}$$

To find B , it is noted that

$$B/B_0 = \frac{1}{2} (V/V_0 + 1) = 4.5$$

hence

$$B = (4.5)(425) = 1920 \text{ gauss}$$

The current per space charge spoke is

$$I_o = 170 (.025)^3 (1.5) \left(\frac{0.15''}{0.04''} \right) \text{ amperes} = 15 \text{ ma.}$$

where W has been assumed to be 0.15 inch. Assuming that unit current flows, the maximum generated R. F. power per spoke at the output end is

$$\frac{1}{2} \times 15 \times 1.28 = 9.6 \text{ watts}$$

For an output power level of 200 watts, the gain per spoke is

$$10 \log \frac{200}{190.4} = 0.22 \text{ db}$$

Since more than one unit of current can be drawn, a gain of 0.5 db per spoke is reasonable. For a total gain of 20 db, therefore, 40 spokes are required. This requires that the anode have a length of

$$40 \lambda_a = 40(0.15 \text{ cm.}) = 6 \text{ cm.}$$

The anode may conveniently be formed of a helix having a pitch of $\frac{1}{4}$ to $\frac{1}{6} \lambda_a$; as an example $\frac{1}{4} \lambda_a = 0.04$ cm. The circumference of the helix is the $\frac{1}{4} \lambda_o = 1.5$ cm., so that the helix diameter is

$$\frac{1.5}{\pi} = 0.48 \text{ cm.}$$

In Figs. 2 and 3, I show an illustrative embodiment of my invention. The R. F. structure is enclosed in a suitable evacuated vessel 3. The input signal is applied

4

through a coaxial line 4 via suitable impedance matching devices (not shown) to the anode 5, and the signal wave propagates along the transmission line comprising the anode 5 and cathode 6. Under the influence of the applied transverse electric and magnetic fields, electrons from cathode 6 interact with the signal, and amplification takes place as hereinbefore explained. Heating power is supplied to cathode 6 via lines 7. The D. C. electric field is applied between one of lines 7 and anode 5, as shown. The amplified output energy is coupled via impedance matching devices (not shown) to coaxial line 8.

In Fig. 3 a section of the amplifier, along lines 3-3 high, is shown in which corresponding parts are given like reference numerals. In addition magnetic poles 9 and 10 which supply the transverse magnetic field are shown.

While I have described above the principles of my invention in connection with a particular embodiment, it is to be clearly understood that this description is made only by way of example and not as a limitation to the scope of my invention. In particular the invention is not limited to a linear magnetron, as it is apparent that other structures might be used. For example, a circular magnetron which is not re-entrant and in which the input and output circuits are isolated from one another may be used. Again, the invention is not limited to the helical type of anode, as other types of known transmission lines on which waves propagate at reduced velocity may be used.

30 What I claim is:

In a broad band microwave amplifier, a two element substantially rectilinear transmission line for propagating electromagnetic waves, comprising two spaced conductive elements, one of said elements comprising an inductively loaded anode consisting essentially of a helically shaped metallic structure, and the other of said elements comprising an electron emissive cathode extending along the length of said line, means for producing a unidirectional electric field between said two elements, means for producing between said elements a magnetic field perpendicular to said electric field, and to said line means for applying radio frequency energy to one end of said transmission line and output means coupled to the other end of said transmission line.
